UNITED STATES PATENT OFFICE.

CHARLES W. BRABBÉE, OF BRONXVILLE, NEW YORK, ASSIGNOR TO AMERICAN RADIATOR COMPANY, OF NEW YORK, N. Y., A CORPORATION OF NEW JERSEY.

HEATING STOVE.

Application filed January 2, 1926. Serial No. 78,762.

My invention relates broadly and generally to new and useful improvements in heating stoves, and more particularly of that character or type wherein the heat generated by burning of a suitable fuel is imparted by radiation, convection, and conduction to the atmosphere of a room or other space in which the stove may be located.

The primary object of the invention is to provide a stove for house-heating purposes, which will be simple in construction, comparatively small in volume, and which may be operated at high heating efficiency with a comparatively small consumption of fuel. A further object is to produce an efficient heating stove which not only will be operated by small quantities of fuel, but which requires replenishment of fuel only at long intervals, and thus be economical in operation and require a minimum of service.

A further object is to provide a stove of the character stated, which will operate efficiently on substantially any grade of commercial, solid fuel, and especially soft coal and wood, with a minimum amount of smoke.

A further object is to provide a stove which will begin promptly to give off heat efficiently within a very short period after a fire is kindled, and which will in effect store the heat generated therein and continue to transmit the heat for a considerable period after the fire may have subsided or died out.

A further object is to provide a stove which in its preferred embodiment will occupy but small space, but which will generate sufficient heat to efficiently warm a comparatively large room or apartment, and which will radiate heat toward the lower portion of the room, and especially the floor.

Other objects will be apparent from the specifications hereinafter set forth.

The invention consists in the improved construction, arrangement and combination of parts, to be more fully set forth herein-after, and the novelty of which will be particularly pointed out and distinctly claimed.

In the accompanying drawings, to be tak-

en as a part of these specifications, I have fully and clearly illustrated a preferred embodiment of my invention, and wherein—

Figure 1 is a view in front elevation of a preferred embodiment of my invention; Fig. 2 is a vertical, central section on the line 2—2 of Fig. 1;

Fig. 3 is a top, plan view of a base structure;

Fig. 4 is a top, plan view of an ash-pit section with the body portion of the stove removed;

Fig. 5 is a top, plan view of a grate-supporting member;

Fig. 6 is a top, plan view of means for supporting or retaining a stove lining in place in the body portion and for supporting a baffle wall or curtain;

Fig. 7 is a detail, front view of a baffle wall or curtain;

Fig. 8 is a section on the line 8—8 of Fig. 1;

Fig. 9 is a section similar to Fig. 2 but showing another embodiment or development of the same invention.

1 designates a base or stand upon which the other parts of the stove are assembled and supported. In the preferred embodiment this base includes a horizontal platform or table 2, substantially rectangular in plan view and supported at its corners by feet 3 which may be cast integral therewith, or be of any suitable detachable construction, as may be desired. This platform is provided on its supporting surface with a peripheral, upstanding bead or flange 4, preferably cast with the body of the platform, and located inward from the outer edges of the latter, so that the platform is provided with a marginal bearing face 5 surrounding said bead.

Supported on the marginal face 5 is an ash-pit section 6, preferably of cast metal and including a front wall 7, side walls 8 and a rear wall 9, the lower edges of which rest on said face 5, so that the lower portion of the ash-pit section is closed by the platform 2 which constitutes the bottom wall of the ash-pit section. The front wall is pro-

vided with an opening 10 through which access may be had for removal of ashes from the ash-pit, said opening having a hinged closure plate or door 11 of well-known form 5 provided with draft opening 12 and slideable closure plate 13 controlling the same. In Fig. 1 the plate 13 is shown in position to uncover opening 12 to admit air to the ash-pit. The walls of the ash-pit section are 10 preferably inclined or tapered inward toward the upper portion, and at the upper end the section is provided with an inwardly directed, continuous flange 14 having an intermediate, upstanding bead or flange 15 15 dividing said flange into inner and outer bearing or supporting faces 16, 17, respectively. Resting on the flange face 16 is a rectangular grate-supporting plate 18 held in place by contact of its side faces with the 20 adjacent faces of said bead 15. This plate 18 is formed with a central, circular opening 19, and extending downward and inward from said plate are supporting lugs 20. Arranged within the circular opening 19 and 25 supported upon said lugs 20 is a rotary grate 21, circular in contour, and having inwardly directed, spaced fingers 22 terminating some distance short of the center of the plate to provide a central space 23. Certain of the 30 fingers which are opposite to each other are provided with depending and inwardly directed lugs 24, upon which is slidably arranged a reciprocating, perforated grate section 25 and protruding through an opening 35 in the side wall 8 of the stove is a shaker arm 26, see Figs. 1 and 8. By applying a suitable shaker-bar to the arm 26, the latter may be swung from side to side to oscillate the entire grate structure, inclusive of the 40 plate 21 and part 25, or the part 25 may be reciprocated forward and backward. The reciprocations of the part 25 are guided by means of extension fingers 27 cooperating with said lugs 24, and also by engagement of 45 a depending finger 28 on plate 21 with a slotted fork 29 straddling the arm 26. The arrangement just described also provides such connection between part 25 and the plate 21 that the latter may be rotated as 50 described.

Arranged above the ash-pit section is a fire-pot or body portion, shown generally at 30, the same being substantially rectangular in cross-section on any horizontal line, and 55 comprising a front wall 31, rear wall 32, and side walls 33, preferably cast in an integral metal structure. The bottom of the shell of the fire-pot is open and the lower edges of the walls rest on the outer, supporting surface 17 heretofore described. From the lower edge of the shell the walls of the ash-pit section and fire-pot member are flared upward to the top of the fire-pot, as 60 will be apparent from Figs. 1 and 2 of the drawings, i. e., has equally inclined walls 65

diverging gradually upward such that said fire-pot is of gradually increasing horizontal cross-sectional area. It will be seen that the chamfered face 18^a, the top of bead 15 and the adjacent portion of the fire-pot wall or 70 shell constitute a groove or seat which retains the lower edges of the fire-brick.

The front wall of the fire-pot section is provided with a fuel inlet chute 36 suitably secured to said wall and closed by a hinged 75 door 37 having openings 38 therethrough controlled by a slideable closure-plate 39. The opening may be opened to admit air to the fire-pot in a manner and for a purpose to be presently set forth. The lower portion 80 of the door may be provided with openings 40 closed by mica, which is protected from heat and flame by a gauze screen 41, supported in rear thereof by the door 37, and in the lower edge of the door are inlet openings 42 delivering secondary air between the door and the screen, so that the air may pass over the screen into the fire chamber over the fuel. It will be noted that the fire-pot is substantially symmetrical in cross- 85 section, and that the center of the grate is located on the vertical, center axis of the fire-pot. It will also be noted that the grate area is small compared to the cross-sectional area of the section 30. 90

The walls of the fire-pot section are lined with a suitable refractory, preferably comprising lower and upper fire-brick blocks 43, 44, which rest against said walls, said lining extending preferably from the extreme bottom of the fire-pot adjacent the grate, to a point adjacent the top of the fire-pot and above the upper edge of the fuel opening 36. The lower fire-bricks or blocks rest on and are supported at their lower portions 100 upon the upper surface of the bead 15 and against a chamfered face 18^a on the plate 18, the lower portions of said blocks being each provided with a horizontal face 44^a and a 105 chamfered face 45.

It will be noted, particularly upon reference to Fig. 8, that each set of fire-brick blocks 43, 44, respectively, includes four slabs, each of which rests against an adjacent wall of the fire-pot member 30. The 110 side and back blocks are provided with chamfered side faces 45^a, and the front and rear blocks are provided with angular portions 46, also provided with chamfered end faces which engage the adjacent faces 45^a 115 on the side blocks. By this arrangement when the blocks or slabs are placed in position, they cooperate to hold each other against the side walls of the fire-pot member—that is, to prevent inward displacement from operative position. As will be 120 apparent from Fig. 2 of the drawings, the upper edge portions of the lower blocks 43 are provided with faces 47 which are in a 125 plane substantially at right angles to the 130

front and rear faces of the blocks, so that when the blocks are located in position said faces 47 are inclined to the horizontal, and the lower faces of the upper blocks 44 are 5 formed to correspond to the faces 47 and rest thereon, so that the upper blocks interlock with the lower blocks and inward displacement of the upper blocks is prevented at this point.

10 At the upper portion of the fire-pot the upper, refractory blocks at the sides and rear walls are held in place by a retaining member in the form of a rectangular frame, including a horizontal portion 48 adapted to 15 rest on the upper edges of the blocks, and an internal flange 49 extending downward into engagement with the upper portions of the inner faces of the fire-bricks. This retaining member rests by its own weight on 20 the fire-bricks, and due to its rigidity maintains the latter in position without the necessity of additional securing means.

The upper edge of the front block 43 terminates just below the lower edge of the fuel 25 inlet and is held in place by a retaining plate 50, which is secured by a bolt 51 to the lower wall of element 36. Should replacement of the blocks be necessary, the member 48 may be readily raised from position 30 to permit removal of the side and rear blocks, and after insertion of new blocks, may be with facility replaced in its holding position in engagement therewith. The front block may be replaced by detaching 35 the plate 50.

That portion of the flange 49 which depends from the front, transverse member of the retaining frame, is provided with an inwardly directed flange or lip 48^a forming 40 an upwardly opening groove 48^b which serves a purpose to be presently set forth.

Extending from a point at the front wall 45 above the fire door, and extending downward and rearward toward the rear wall and fuel bed, is a baffle or curtain wall 52, preferably of cast-iron, said baffle being curved as shown, and having its lower end located nearer the rear wall than the front wall and preferably at a point approxi- 50 mately at the level of the lower wall of the fuel inlet, as at 53. The said lower, rear edge is preferably located midway between the vertical center of the fire-pot and the inner surface of the rear wall. It will be 55 seen that the baffle divides the fire-pot transversely into a large, primary combustion chamber 54, and a rear, restricted outlet throat 55, the latter being formed by the baffle and the rear wall of the fire-pot. It 60 will also be seen that the front and side walls of the primary combustion chamber are lined by the refractory, and that the outlet throat is lined with refractory on its side and rear walls. By the arrangement just 65 described, when the fuel level is approxi-

mately at the line A—A, and the fire is burning, and when air is admitted over the fuel in front of the baffle—for example, through the fuel inlet or the opening 70 through the fire door—the air is deflected by the baffle on to the bed of fuel and is drawn with the products of combustion and unignited gases beneath the lower edge of the baffle into the restricted throat 55. In the throat the unignited gases, etc., are projected against the hot refractory, and are there ignited, so that more perfect combustion of the fuel is assured, and production 75 of smoke materially reduced.

In its preferred embodiment, the baffle is 80 braced and strengthened by integral, transverse and longitudinal intersecting ribs 56, 57, the latter being of increasing depth from top to bottom of the plate and terminating at their lower portions in teeth or projections 58 which extend below the lower edge of the plate. Between the ribs 57 are a plurality of vertical ribs 57^a, the upper ends of which terminate below the lower, transverse rib, said ribs 57^a being similar in construction to ribs 57 and terminating in like manner at their lower ends in teeth 58^a. By means of the increased depth of the longitudinal ribs 57, 57^a and the projections 58, 58^a, the fuel is prevented from being packed 90 against the lower portion of the baffle, and is held away therefrom so as to provide unobstructed vertical spaces or passages between the ribs for free flow of air and gases 95 from the combustion chamber between the fuel and the baffle and beneath the latter into the throat 55.

The baffle or curtain is preferably supported at its forward and upper edge by means of a flange or rib 59 seated in the groove seat 48^b, heretofore described, and if desired the supporting connection may be made rigid by means of overlying clip-plates 60 secured by screws to the transverse front frame member and the adjacent portion of 100 the baffle. By the means described, a simple and effective means is provided for detachably securing the baffle in place and permitting easy assembly thereof.

Arranged above the fire-pot member is a 115 head or dome 61, which is substantially rectangular in cross-section, having a front wall 62, rear wall 63, side walls 64, and a top crown wall 65, the walls of the dome forming continuations of the side walls of the fire-pot member, and the interior of the dome forming, together with the space in rear of and above the baffle, a secondary combustion chamber into which the products of combustion are delivered from the restricted throat 55 heretofore described. The lower edge of the dome is formed with a surrounding bearing face 66 adapted to rest upon the horizontal, upper edge of the fire-pot, and with an external, depending flange 120 125 130

67 having an outwardly flared bearing face 68 adapted to seat upon an inclined or chamfered face 69 on the top of the fire-pot, so that the dome, by its weight, rests solidly 5 upon the upper edge of the fire-pot, and a smoke and gas-tight joint is afforded. The rear wall of the dome is provided with a smoke outlet duct 70, preferably cast integral therewith, and by which connection is 10 made to a suitable smoke pipe (not shown) leading to a chimney, said duct being located below the crown or top wall.

The dome is preferably made in an integral structure of cast-iron, and is not lined, 15 so that it is quickly heated and efficiently radiates its heat to the surrounding atmosphere.

The construction and arrangement of the parts being as above described, the operation 20 of the stove is as follow: The fire is kindled in any suitable manner, and the fire-pot is supplied with any suitable solid fuel, such as coal, coke or wood, to a level substantially in line with the lower portion of the fuel 25 inlet, the level of the fuel closely approaching the lower, rear edge of the baffle 52. When the fire is first kindled, the refractory lining will not at once be heated, but the hot products of combustion passing through 30 the throat 55 enter the head or dome 61 and the walls of the latter are quickly heated so that the stove will begin to transmit its heat very shortly after the fire has been started. As soon as the fire is burning normally, the 35 refractory becomes heated, and then efficient transmission will take place from the fire-pot walls. During this period the fuel, if coal, becomes coked. When refiring the coke is pushed back and under the baffle closing 40 the space between the lower portion of the baffle and the rear refractory wall 44, whereupon fuel is supplied to a desired level, for example A'-A', so as to rest against the front of the baffle. The air entering through 45 openings 38 in the fire-door passes over and through the fuel and down between the ribs 57, 57^a, and between the teeth 58, 58^a into the restricted throat. It will also be found that should the fire go out, the stove will 50 continue to radiate heat for a considerable period, due to the heated refractory continuing to give off heat stored therein during the burning of the fuel. In cases where soft or smoking coal is used, the opening through 55 the fire-door may be opened for a suitable distance to admit air over the fuel bed in front of the baffle, which air, being deflected by the baffle upon the fuel bed and drawn through the latter, will mix with the products 60 of combustion and unburned gases and pass with the same into the restricted throat where the unburned gases will be ignited by contact with the hot refractory lining forming the back and side walls of the throat, and 65 thus reduce smoke to a minimum. The prod-

ucts of combustion pass from the throat into the dome and there give off heat to the walls of the dome. The products in passing from the throat into the dome are directed toward the front of the latter so as to circulate in contact with the wall of the dome before passing out of the outlet duct. If desired, additional secondary air may be supplied to the throat 55, through an inlet port 55^a, through the side wall of the stove, 75 which port may be screened by a mesh 55^b, and covered by a movable cover-plate 55^c. The plate 55^c may be opened during the periods of kindling and refiring.

In the modified form shown in Fig. 9, the air in addition to being admitted to the fire-pot through the fire-door, is admitted through a tube 71 having an inlet end 72 opening through the front wall of the dome, said tube extending through the dome to a point substantially central thereof, where it is directed downward and through an opening 73 in the baffle so as to discharge the air on to the fuel bed in front of the baffle. By arranging the air tube to extend through the dome, said tube is heated, and consequently the air flowing therethrough is heated before being discharged into the fire-pot in front of the baffle. The upper end of the air inlet tube may be bolted, as at 74, to the front wall of the dome, whereby said tube is secured rigidly in place. In order to assist in supporting the baffle, the tube preferably is provided with a lug 75 beneath the baffle and upon which the latter rests.

What I claim and desire to secure by Letters Patent of the United States is:—

1. A heating stove comprising an ash-pit, a fire-pot above the ash-pit and having a fuel inlet in its side wall, said fire-pot having substantially equally inclined walls diverging gradually upward such that said fire-pot is of gradually increasing horizontal cross-sectional area, a grate between the ash-pit and fire-pot, and a deflecting baffle supported at its upper portion above the fuel inlet and extending downward and rearward to a point approximating the lower portion of the fuel inlet and at the normal fuel level to divide the fire-pot unequally above the fuel bed into a forward main combustion chamber and a relatively restricted outlet throat at the back of the fire-pot for passage of combustion products from said main chamber.

2. A heating stove comprising an ash-pit, a fire-pot above the ash-pit and having a fuel inlet in its side wall, said fire-pot having substantially equally inclined walls diverging gradually upward such that said fire-pot is of gradually increasing horizontal cross-sectional area, a grate between the ash-pit and fire-pot, a deflecting baffle supported at its upper portion above the fuel inlet and extending downward and rearward

to a point approximating the lower portion of the fuel inlet and at the normal fuel level to divide the fire-pot unequally above the fuel bed into a forward main combustion 5 chamber and a relatively restricted outlet throat at the back of the fire-pot for passage of combustion products from said main chamber, and a refractory lining for said restricted throat adapted to be heated to gas 10 ignition temperature by fire in said fire-pot so that unburned gases are ignited in rear of said baffle by the heat of said refractory lining.

3. A heating stove comprising an ash-pit, 15 a fire-pot above the ash-pit and having a fuel-inlet in its side wall, said fire-pot having substantially equally inclined walls diverging gradually upward such that said fire-pot is of gradually increasing horizontal 20 cross-sectional area, a grate between the ash-pit and fire-pot, a deflecting baffle supported at its upper portion above the fuel inlet and extending downward and rearward to a point approximating the lower 25 portion of the fuel inlet and at the normal fuel level to divide the fire-pot unequally above the fuel bed into a forward main combustion chamber and a relatively restricted outlet throat at the back of the fire-pot for 30 passage of combustion products from said main chamber, and a refractory lining for the fire-pot and extending above the lower edge of said baffle and exposed to gases passing through said throat so that unburned 35 gas is ignited in said throat by the heat of said refractory lining.

4. A heating stove comprising an ash-pit, a fire-pot above the ash-pit and having a fuel inlet in its side wall, said fire-pot having substantially equally inclined walls diverging gradually upward such that said fire-pot is of gradually increasing horizontal cross-sectional area, a grate between the ash-pit and fire-pot, a deflecting baffle supported at its upper portion above the fuel inlet and extending downward and rearward to a point approximating the lower portion of the fuel inlet and at the normal fuel level to divide the fire-pot unequally above the fuel bed into a forward main combustion 45 chamber and a relatively restricted outlet throat at the back of the fire-pot for passage of combustion products from said main chamber, and means for admitting air above 50 the fuel level and in front of said baffle.

5. A heating stove comprising an ash-pit, a fire-pot above the ash-pit, said fire-pot having substantially equally inclined walls diverging gradually upward such that said fire-pot is of gradually increasing horizontal cross-sectional area, a grate between the ash-pit and fire-pot, said fire-pot having front and rear walls, the front wall having a fuel inlet, and a depending deflecting baffle 60 extending from the front wall above the fuel

inlet downward and rearward toward said rear wall, said baffle having its lower edge portion located at approximately the lower portion of the fuel inlet and at the normal fuel level and nearer to the rear wall than the front wall so as to divide the fire-pot above the normal fuel level into a forward main fuel chamber and a relatively restricted outlet throat at the back of the fire-pot for combustion products from said main chamber.

6. A heating stove comprising an ash-pit, a fire-pot above the ash-pit, said fire-pot having substantially equally inclined walls diverging gradually upward such that said fire-pot is of gradually increasing horizontal cross-sectional area, a grate between the ash-pit and fire-pot, said fire-pot having front and rear walls, the front wall having a fuel inlet, a depending deflecting baffle extending from the front wall above the fuel inlet downward and rearward toward said rear wall, said baffle having its lower edge portion located at approximately the lower portion of the fuel inlet and at the normal fuel level and nearer to the rear wall than the front wall so as to divide the fire-pot above the normal fuel level into a forward main fuel chamber and a relatively restricted outlet throat at the back of the fire-pot for combustion products from said main chamber, and a dome of heat-conducting material above the fire-pot and receiving the hot gases from said restricted throat outlet.

7. A heating stove comprising an ash-pit, a fire-pot above the ash-pit, said fire-pot having substantially equally inclined walls diverging gradually upward such that said fire-pot is of gradually increasing horizontal cross-sectional area, a grate between the ash-pit and the fire-pot and substantially concentric with the fire-pot, said fire-pot having front and rear walls, a fuel inlet through the upper portion of said front wall, a refractory lining for the fire-pot and extending from below the fuel level to the upper portion of the fire-pot, and a baffle supported adjacent the front wall above the fuel inlet and extending downward and rearward toward said rear wall so that its lower rear edge portion is adjacent the fuel level and nearer the rear wall than the front wall, thereby dividing the cross-sectional area of the fire-pot into a forward main fuel chamber and a rear relatively restricted outlet for passage of combustion products from said main chamber.

8. A heating stove comprising an ash-pit, a fire-pot above the ash-pit, said fire-pot having substantially equally inclined walls diverging gradually upward such that said fire-pot is of gradually increasing horizontal cross-sectional area, a grate between the ash-pit and the fire-pot and substantially concentric with the fire-pot, said fire-pot having

- front and rear walls, a fuel inlet through the upper portion of said front wall, a refractory lining for the fire-pot and extending from below the fuel level to the upper portion of the fire-pot, and a baffle supported adjacent the front wall above the fuel inlet and extending downward and rearward toward said rear wall so that its lower rear edge portion is adjacent the fuel level and nearer the rear wall than the front wall, thereby dividing the cross-sectional area of the fire-pot into a forward main fuel chamber and a rear relatively restricted outlet for passage of combustion products from said main chamber and a rear relatively restricted outlet for passage of combustion products from said main chamber, the refractory lining of the fire-pot rear wall constituting the rear wall of said outlet so that unconsumed gases are ignited in rear of the baffle by the heat of said restricted throat lining, and a dome above the fire-pot concentric therewith and constituting a combustion chamber, said dome being of unlined metallic material subject to the direct effect of the heat of the gases therein and constituting a heat-emitting element.
11. A heating stove comprising an ash-pit, a fire-pot above the ash-pit, a grate between the ash-pit and the fire-pot, a fuel inlet to the fire-pot, lower refractory lining blocks within the fire-pot and supported therein, upper refractory lining blocks, supported on said lower blocks, the plane of the meeting faces of a lower block and its upper supported block being inclined downward from a horizontal plane toward the outside of the fire-pot whereby the upper block is held at its lower end against movement inwardly in a horizontal plane, and a retaining frame resting upon the upper ends of the upper blocks and maintaining the upper ends of said upper blocks against movement inwardly in a horizontal plane.
12. A heating stove comprising an ash-pit, a fire-pot above the ash-pit, a grate between the ash-pit and the fire-pot, a fuel inlet to the fire-pot, lower refractory lining blocks within the fire-pot and supported therein, an inclined seat adjacent the grate, the lower ends of said blocks having faces cooperable with said seat to retain said blocks against inward movement, upper refractory lining blocks supported on said lower blocks, the plane of the meeting faces of a lower block and its upper supported block being inclined downward from a horizontal plane toward the outside of the fire-pot whereby the upper block is held at its lower end against movement inwardly in a horizontal plane, and a retaining frame resting upon the upper ends of the upper blocks and maintaining the upper ends of said upper blocks against movement inwardly in a horizontal plane.
13. A heating stove comprising an ash-pit, a fire-pot above the ash-pit, a grate between the fire-pot and the ash-pit, a fuel inlet to the fire-pot, refractory lining blocks within the fire-pot and extending to a point approximating the upper portion of the fuel inlet, a retaining frame at the upper portion of said blocks for maintaining the same in position and including a member carried by said frame and located adjacent the upper portion of the fuel inlet, and a downwardly

the rear wall than the front wall, thereby dividing the cross-sectional area of the fire-pot into a forward main fuel chamber and a rear relatively restricted outlet for passage of combustion products from said main chamber, the refractory lining of the fire-pot rear wall constituting the rear wall of said outlet so that unconsumed gases are ignited in rear of the baffle by the heat of said restricted throat lining, and a dome above the fire-pot concentric therewith and constituting a combustion chamber, said dome being of unlined metallic material subject to the direct effect of the heat of the gases therein and constituting a heat-emitting element.

11. A heating stove comprising an ash-pit, a fire-pot above the ash-pit, a grate between the ash-pit and the fire-pot, a fuel inlet to the fire-pot, lower refractory lining blocks within the fire-pot and supported therein, upper refractory lining blocks, supported on said lower blocks, the plane of the meeting faces of a lower block and its upper supported block being inclined downward from a horizontal plane toward the outside of the fire-pot whereby the upper block is held at its lower end against movement inwardly in a horizontal plane, and a retaining frame resting upon the upper ends of the upper blocks and maintaining the upper ends of said upper blocks against movement inwardly in a horizontal plane.

12. A heating stove comprising an ash-pit, a fire-pot above the ash-pit, a grate between the ash-pit and the fire-pot, a fuel inlet to the fire-pot, lower refractory lining blocks within the fire-pot and supported therein, an inclined seat adjacent the grate, the lower ends of said blocks having faces cooperable with said seat to retain said blocks against inward movement, upper refractory lining blocks supported on said lower blocks, the plane of the meeting faces of a lower block and its upper supported block being inclined downward from a horizontal plane toward the outside of the fire-pot whereby the upper block is held at its lower end against movement inwardly in a horizontal plane, and a retaining frame resting upon the upper ends of the upper blocks and maintaining the upper ends of said upper blocks against movement inwardly in a horizontal plane.

13. A heating stove comprising an ash-pit, a fire-pot above the ash-pit, a grate between the fire-pot and the ash-pit, a fuel inlet to the fire-pot, refractory lining blocks within the fire-pot and extending to a point approximating the upper portion of the fuel inlet, a retaining frame at the upper portion of said blocks for maintaining the same in position and including a member carried by said frame and located adjacent the upper portion of the fuel inlet, and a downwardly

and rearwardly directed baffle having its upper portion supported by said member, and said baffle depending within the fire-pot to divide the same into a main combustion chamber and an outlet passage in rear of the baffle.

14. A heating stove comprising an ash-pit, a fire-pot above the ash-pit, a grate between the ash-pit and the fire-pot, a fuel inlet to the fire-pot, a refractory lining for the fire-pot, a retaining frame engaging the lining at a point approximating the upper portion of the fuel inlet, said frame having a channel member adjacent the fuel inlet, a deflecting baffle extending downward and rearward from above the fuel inlet, said baffle having means engaging the channel of said channel member whereby said baffle is supported, and said baffle dividing the fire-pot above the normal fuel level into a forward main combustion chamber, and an outlet passage at the rear of the fire-pot for passage of combustion products from said main chamber.

15. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber, a restricted outlet throat at the back of the fire-pot for passage of combustion products from said main chamber, and an air inlet tube extending downward through said baffle into said main combustion chamber.

16. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber, a restricted outlet throat at the back of the fire-pot for passage of combustion products from said main chamber, a dome above the fire-pot and receiving the hot gases from said restricted throat outlet, and an air inlet tube located in said dome to be heated by the gases therein, said tube having an inlet end opening through the wall of the dome and its outlet end arranged to discharge air beneath said baffle.

17. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and

rearward to a point approximating the lower portion of the fuel inlet and at the normal fuel level to divide the fire-pot above the fuel bed into a forward main combustion chamber, a restricted outlet throat at the back of the fire-pot for passage of combustion products from said main chamber, a dome above the fire-pot and receiving the hot gases from said restricted throat outlet, and an air inlet tube located in said dome to be heated by the gases therein, said tube having an inlet end opening through the wall of the dome, and its outlet end projecting through said baffle into the main combustion chamber to discharge air in front of said baffle.

18. A heating stove comprising an ash-pit member having side walls and a horizontal platform having an intermediate perimetral bead dividing said platform into outer and inner bearing faces, a grate member supported on said inner bearing surface, a fire-pot resting on said outer bearing surface, said grate member having a part projecting above said bead and forming with the fire-pot a groove, a refractory lining for the fire-pot and having its lower portion seated in said groove and thereby held against inward movement relative to the fire-pot wall, said refractory lining extending to the upper portion of the fire-pot above the fuel level, and means engaging the upper portion of the refractory lining for securing the same in position relative to the fire-pot wall.

19. A heating stove comprising an ash-pit, a fire-pot above the ash-pit, said fire-pot having substantially equally inclined walls diverging gradually upward such that said fire-pot is of gradually increasing horizontal cross-sectional area, a grate between the fire-pot and the ash-pit, a dome above the fire-pot and constituting a heat-emitting element, said fire-pot and dome being of substantially rectangular cross-section, a fuel inlet through the upper portion of the fire-pot wall, a baffle supported at its upper part above the fuel inlet and extending therefrom downward and rearward with its lower edge portion arranged between the vertical axis of the fire-pot and the rear wall thereof, and having its lower end located at approximately the lower portion of the fuel inlet and at the normal fuel level, whereby the fire-pot beneath the baffle is unobstructed for the reception of fuel, and that portion of the fire-pot above the fuel level is divided into a forward main combustion chamber, and a rear restricted throat through which products pass from said main combustion chamber and also from the fuel in rear of the throat into said throat and to said dome.

20. A heating stove comprising an ash-pit, a fire-pot above the ash-pit, a grate between the fire-pot and the ash-pit, a dome above the fire-pot and constituting a heat-

emitting element, said fire-pot and dome being of substantially rectangular cross-section, a fuel inlet through the upper portion of the fire-pot wall, a baffle supported at its upper part above the fuel inlet and extending therefrom downward and rearward with its lower edge portion arranged between the vertical axis of the fire-pot and the rear wall thereof, and having its lower end located at approximately the lower portion of the fuel inlet and at the normal fuel level, whereby the fire-pot beneath the baffle is unobstructed for the reception of fuel, and that portion of the fire-pot above the fuel level is divided into a forward main combustion chamber, a rear restricted throat through which products pass from said main combustion chamber and also from the fuel in rear of the throat into said throat and to said dome, and a refractory lining for the fire-pot supported on said ash-pit and extending upwardly substantially to the horizontal plane of the top of said baffle.

25 21. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber, and a restricted outlet throat at the back of the fire-pot for passage of combustion products from said main chamber, said baffle having substantially vertical ribs on its forward face forming flow passages and having projections along its lower edge to hold the fuel out of contact with the face of the baffle, said ribs and projections providing for free flow of air and gases from the combustion chamber between the fuel and said baffle and beneath said baffle to said throat.

22. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber, and a restricted outlet throat at the back of the fire-pot for passage of combustion products from said main chamber, said baffle having substantially vertical ribs on its forward face extending downward and forming flow passages terminating in teeth or projections extending below the lower edge of the baffle, said ribs and teeth serving to hold the fuel out of con-

tact with the face of the baffle and providing for free flow of air and gases from the combustion chamber between the fuel and said baffle and beneath said baffle to said throat.

23. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber, and a restricted outlet throat at the back of the fire-pot for passage of combustion products from said main chamber, said baffle having spaced projections or teeth along its lower edge to hold the fuel out of contact with the face of the baffle to provide flow passages for flow of air and gas from the combustion chamber to said throat.

24. A heating stove comprising an ash-pit, a fire-pot above the ash-pit and having a fuel inlet in its side wall, a grate between the ash-pit and fire-pot, a deflecting baffle supported at its upper portion above the fuel inlet and extending downward and rearward to a point approximating the lower portion of the fuel inlet and at the normal fuel level to divide the fire-pot above the fuel bed into a forward main combustion chamber and a restricted outlet throat at the back of the fire-pot for the passage of combustion products from said main chamber, means opening through said baffle for admitting air above the fuel level in front of said baffle, and means for admitting air to said restricted outlet throat and above the fuel level.

25. A heating stove comprising an ash-pit, a fire-pot above the ash-pit, a grate between the ash-pit and the fire-pot, a fuel inlet to the fire-pot, lower refractory lining blocks within the fire-pot and supported therein, upper refractory lining blocks supported on said lower blocks, the plane of the meeting faces of a lower block and its upper supported block being inclined downward from a horizontal plane toward the outside of the fire-pot whereby the upper block is held at its lower end against movement inwardly in a horizontal plane.

26. A heating stove comprising an ash-pit member having side walls and a horizontal platform having an intermediate perimetral bead dividing said platform into outer and inner bearing faces, a grate member supported on said inner bearing surface, a fire-pot resting on said outer-bearing surface, said grate member having a part projecting above said bead and forming with the fire-pot a groove, a refractory lining for the fire-

pot and having its lower portion seated in said groove and thereby held against inward movement relative to the fire-pot wall, said refractory lining extending to the upper portion of the fire-pot above the fuel level, means engaging the upper portion of the refractory lining for securing the same in position relative to the fire-pot wall, and a baffle supported by said means and depending therefrom to divide said fire-pot into a main combustion chamber and an outlet throat.

In testimony whereof I have hereunto subscribed my name.

CHARLES W. BRABBÉE.
